UNITED STATES PATENT OFFICE.

JOSEPH F. RIVARD, OF DETROIT, MICHIGAN.

DESIGN FOR A COMBINED REAR AND SIDE VIEW MIRROR FOR AUTOMOBILES.

Application filed May 4, 1927. Serial No. 21,859. Term of patent 7 years.

To all whom it may concern:

Be it known that I, JOSEPH F. RIVARD, a citizen of the United States, residing at Detroit, in the county of Wayne and State of Michigan, have invented a new, original, and ornamental Design for Combined Rear and Side View Mirrors for Automobiles, of which the following is a specification, reference being had to the accompanying drawing, forming a part thereof, in which—

Fig. 1 is a front elevation.

Fig. 2 is a plan view, and

Fig. 3 is a side elevation of a mirror embodying my design.

I claim:

The ornamental design for a combined rear and side view mirror for automobiles as shown.

JOSEPH F. RIVARD.
